UNITED STATES PATENT OFFICE.

PETER FRANDSEN, OF MONETT, MISSOURI.

SAFETY SWITCH STAND.

Application filed February 5, 1926, Serial No. 86,287. Renewed November 14, 1927.

This invention relates broadly to new and useful improvements in railroad appliances and has more particular reference to a novel and simplified construction of switch stand.

5 An important object of the present invention is to provide a switch stand so constructed that upon the operation of the same, the switch points will be moved with efficiency and reliability to assume the desired positions.

Another important object of the present invention is the provision of such a switch stand wherein the switch points will be effectively locked against accidental movement.

15 Another object of the invention is to provide such a switch stand embodying a pair of independent locking means so arranged that should one locking means become ineffective for any reason, the other locking means will not in any way be affected thereby.

Another object of the invention is the provision of new and novel dual locking means for a switch stand of the nature stated.

20 Another object of the invention is the provision of such a switch stand which while simple in construction, is nevertheless strong, sturdy and durable, one which is safe, effective and reliable in its operation and well designed for the purposes for which it is intended.

With these and numerous other objects in view, the invention resides in the novel construction, combination and arrangement of parts to be more fully hereinafter described, illustrated in the accompanying drawings and particularly pointed out in the appended claims.

25 In the drawings forming a part of this application and wherein similar characters of reference denote corresponding parts throughout the several views:

30 Figure 1 is a front view, in elevation, of a safety switch stand constructed in accordance with the present invention.

Figure 2 is a side view thereof.

Figure 3 is a top plan view of the same.

35 Figure 4 is a sectional view on line 4—4 of Figure 1.

Figure 5 is a sectional view on line 5—5 of Figure 3.

40 Figure 6 is a top plan view of the bottom rotatable plate.

Figure 7 is a bottom plan view of the disk

adapted to rest upon the plate shown in Figure 6.

Figure 8 is a sectional view taken on line 8—8 of Figure 1.

Figure 9 is a detailed perspective view of the signal standard, per se.

Referring more particularly to the accompanying drawings wherein for the purpose of illustration has been disclosed a preferred embodiment of the present invention, the improved switch stand comprises a substantially rectangular base 10 from the opposite ends of which rise the upwardly extending converging uprights or supports 11 and 12, the lower ends thereof being provided with the angularly directed feet 13 by means of which the same may be secured to the said base through the medium of rail spikes or the like 14.

Carried by the upper ends of the supports 11 and 12 is the semi-circular supporting plate or platform 15, the curved edge thereof projecting forwardly beyond the said supports and being provided with notches 16 and 17. By referring particularly to Figures 2 and 3, it will be noted that the rear straight edge of the platform 15 terminates slightly inwardly of the rear edges of the supports 11 and 12 and that secured to the said rear edge of the platform and also between the said supports, is a transverse brace 18, to the forward face of which is secured the horizontal bearing block 19. Also secured to and extending between the said supports, intermediate the upper and lower ends thereof is a second transverse brace 20.

Secured within the base 10 adjacent the rear edge thereof is the vertically disposed stub shaft 21 on which is mounted the circular plate 22, shown in Figure 6, said plate adapted to rest upon the base 10 and having a central opening for the reception of the said stub shaft and being secured thereon by means of the cotter pin 23, a washer 24 being arranged between the said cotter pin and the upper surface of the plate.

The edge of the plate 22 is formed with notches 25 and 26 while the upper surface thereof is provided with the equally spaced, radially disposed lugs 27 having their side and end edges beveled as shown in the drawings, said plate being so positioned on the base 10 that it projects outwardly and rearwardly thereof. The projecting portion of the plate is provided with an opening 28

through which is inserted the vertical bolt 29 carried by the inner end of the pitman rod 30 which contacts with the bottom surface of the plate 22, a nut 31 being threaded on the upper end of said bolt and held thereon by means of a cotter key 31' passing through the said bolt whereby to secure the pitman rod to the plate 22. The other end of the said rod 30 is adapted to be suitably connected with the switch points of a railway switch.

In Figure 7 is shown a disk 32 which is arranged to rest upon the plate 22 shown in Figure 8, said disk having the central enlarged cut-out portion 33 from which radiate the three equally spaced recesses 34 adapted to receive the lugs 27 on the plate 22, the side faces of the said recesses being beveled to snugly receive the beveled sides of the said lugs, the thickened portions 34' of the disk 32 between the recesses 34 being adapted to rest upon the plate 22, between the lugs 27. Formed within the said disk 32 centrally of the cut-out portion 33 is the circular opening 35 which is reduced and terminates in a square or angular opening 36 and the said disk may be further provided if desired, with a suitable oil hole 33'.

Journalized within the brace 20, bearing block 19 and supporting plate 15 is the vertically disposed shaft or standard 37, carrying at its upper end a suitable signal plate 39 while the lower end thereof is made angular in cross section as indicated at 40 and is received within the angular opening 36 in the disk 32 whereby upon rotary movement of the shaft or standard 37, the disk 32 and plate 22 will also be caused to rotate.

Carried by standard 37 adjacent the angular end 40 thereof is an annular collar 41 formed integral with the standard and provided on its under surface with the diametrically extending beads 42 which are received within similarly positioned grooves 42' (see Figure 3) in the upper surface of the reduced upper end 38 of the disk 32.

Carried by the upper end portion of standard 37 and resting on the said shaft or standard 15 is an arm 43, the outer end portion thereof being formed with the vertically offset head 44 which extends slightly beyond the said platform and is bifurcated to provide the spaced lugs 45 and 46 between which is pivotally mounted, as at 47, the lever 48 which, when in its vertical position, is adapted to be received within either one of the notches 16 and 17 in the platform 15. The upper or inner end of the lever is beveled as at 49 and is adapted to engage the beveled end face 50 of the arm 43 when the said lever is swung into a horizontal position.

For the purpose of locking the lever 48 in its vertical position, there is secured to the forward edge thereof immediately adjacent its upper end an outwardly projecting eye

member 51 which is adapted to pass through the vertical slot 52 in the plate 53 secured to the forward ends of the lugs 45 and 46. When it is desired to lock the lever within either one of the slots 16 or 17, it is only necessary to engage a suitable padlock with the closed pin 51.

Secured to the base 10 directly in front of the plate 22 are the spaced longitudinally extending bearing blocks 55 and 56 between which is positioned the latch member 57, the inner end of which is adapted for selective engagement with the notches 25 and 26 in the plate 22 when the said plate is rotated. Passing through the bearing blocks 55 and 56 and also through the latch 57 is the longitudinally extending shaft 58, said latch being secured thereto by means of a suitable lock screw 59.

The said shaft 58 projects slightly beyond the outer end of the bearing block 55 and secured intermediate its ends to the extended portion of said shaft as by means of the set screw 60 is an arm 61, provided at its forward end with the foot engaging pedal 62 while carried by the opposite end thereof is a weight 63 which normally rests upon the plate 22 and acts to retain the inner end of the latch 57 in engagement with either one of the notches 25 or 26 in the rotatable plate 22.

As hereinabove stated, the pitman rod 30 is adapted to be suitably connected to the movable switch points of a railway switch so that upon reciprocal movement of the said rod, the switch will be thrown from one side to the other.

In the operation of the present invention, when it is desired to throw the switch and for the purpose of illustration, let us say to the left, the operator first steps upon and forces the foot pedal 62 downwardly, thus causing the rotation of the shaft 58 with the result that the latch member 57 carried thereby will be moved upwardly and out of engagement with the notch 26 in the rotatable plate 22. As the operator holds the latch out of engagement with the plate, he should grasp the lever 48 and swing the same outwardly and upwardly about its pivot 47 until it assumes a horizontal position. When this has been done, the rotatable plate and the standard are free to rotate and this is accomplished by simply moving the lever 48 to the right. The standard 37 will then be rotated and this rotation will be imparted to the plate 22 through the disk 32 as described hereinabove. This rotary movement will cause the pitman rod 30 to be moved in the opposite direction or to the left and the movement of this pitman rod will act to cause the railway switch to be thrown and the position of the signal plate 39 will indicate to the engineer of the approaching train whether or not the switch is properly set.

When the switch has been properly closed, the lever 48 will be directly above and in line with the notch 17 in the platform 15 while the notch 25 in the plate 22 will be brought directly opposite the latch 57. As the operator then releases the foot pedal 62, the action of the weight 63 will cause the rotation of the shaft 58 and the latch 57 to gravitate into the notch 25 in the plate 22 and as he then releases the lever 48, the same will gravitate downwardly about its pivot 47 and engage within the notch 17. The engagement of the lever 48 in the notch 17 and the engagement of the latch 57 in the notch 25 of the plate 22 will thus effectively lock the parts so that the railway switch cannot be accidentally thrown.

If it is desired to securely lock the plate 22 and standard 37 against rotation, it is only necessary, as set forth above, to engage a suitable padlock through the eye 51 which will effectively prevent the lever 48 from being swung about its pivot out of engagement with the notch 17.

For the purpose of further locking the switch, there is preferably secured within a recess in the upper surface of the bearing block 55 a plate 65, said plate being positioned immediately adjacent the latch member 57 and provided with an upwardly directed finger 66 which extends beyond the said latch member and is formed with an opening 67 through which is adapted to be inserted any ordinary or preferred type of padlock. This padlock will overlap the latch member 57 and thus effectively prevent the operation thereof.

From the foregoing, it will be readily seen that the latch member 57 prevents the rotation of the plate 22 and the consequential throwing of the railway switch while the lever 48 engaging the platform 15 prevents the rotation of the standard 37. In view of this, it will be appreciated that should the upper portion of the switch stand become broken or otherwise damaged, the latch 57 will still lock the plate 22 against rotation and prevent the throwing of the switch while, should the latch 57 become inoperative, for one reason or another, the lever 48 engaging the platform 15 will prevent the rotation of the standard and the accidental throwing of the switch. Thus, a dual safety means has been provided for preventing the accidental throwing of the railway switch and that while there has been described hereinabove and illustrated in the accompanying drawings a preferred embodiment of the present invention which in practice will accomplish all of those objects and perform all of the functions enumerated as being desirable in the statement of invention hereinabove set forth, it is to be understood that the same is susceptible of modifications in various particulars and that any such

modifications as properly fall within the scope of the appended claims may be resorted to without departing from or sacrificing the spirit of the invention.

What is claimed is:

1. In a switch stand of the class described, a base, a supporting platform carried by said base, a member rotatably mounted upon said base, a substantially vertically disposed standard journaled in said platform, and having connection with said member, means carried by the base and movable into and out of engagement with the member to prevent rotary movement thereof, and means carried by said standard for cooperation with said platform for preventing rotation of the said standard.

2. In a switch stand of the class described, a base, a member rotatably mounted upon said base, a pitman rod connected to and movable with said member and adapted to be suitably connected with the switch points of a railway switch, a substantially vertically disposed standard rotatable with said member, and means, upon the base, movable into and out of engagement with said member for locking the same and the standard against rotary movement.

3. In a switch stand of the class described, a base, a plate rotatably mounted upon said base and provided with notches, a pitman rod carried by and movable with said plate and adapted to be suitably connected with the switch points of a railway switch, a substantially vertically disposed standard rotatable with said plate, a latch adapted for selective engagement with said notches whereby to lock said plate and standard in desired position, and manually operable means for moving the said latch from engagement with said notches when it is desired to rotate the said plate and standard.

4. In a switch stand of the class described, a base, a rotatable plate mounted upon said base and provided with notches, a pitman rod connected with said plate and adapted to be suitably connected with the switch points of a railway switch, a latch carried by said base adjacent the said plate, means for normally holding the latch in position for selective engagement in said notches when the plate is rotated to bring the notches into alignment with said latch, and manually operable means for releasing the said latch from engagement with said notches.

5. In a switch stand of the class described, a base, a rotatable plate mounted upon said base and provided with notches, a pitman rod connected with said plate and adapted to be suitably connected with the switch points of a railway switch, a substantially vertically disposed standard supported by and movable with said plate, a latch carried by said base, and means for causing the latch to engage, by gravity, in the said notches.

when the said plate is rotated to aline the said notches with the said latch whereby to prevent the rotation of said plate and standard.

- 5 6. In a switch stand of the class described, a base, a rotatable plate mounted upon said base and provided with notches, a pitman rod connected with said plate and adapted to be suitably connected with the switch 70 points of a railway switch, a disk removably supported upon said plate and rotatable therewith, a substantially vertically disposed standard engaged with said disk, and means for rotating said standard whereby 10 to impart rotary movement to the said disk 15 and plate.

7. In a switch stand of the class described, a base, a rotatable plate mounted upon said plate and provided with notches, a pitman 20 rod connected with said plate and adapted to be suitably connected with the switch points of a railway switch, a disk removably supported upon said plate and rotatable therewith, a substantially vertically disposed 25 standard engaged with said disk, means for rotating said standard whereby to impart rotary movement to the said disk and plate, and means carried by the base and engageable with said plate for locking the same and 30 the standard against rotation, when so desired.

8. In a switch stand of the class described, a base, a rotatable plate mounted upon said base and provided with notches, a pitman 35 rod connected with said plate and adapted to be suitably connected with the switch points of a railway switch, a disk removably supported upon said plates and rotatable therewith, a substantially vertically disposed 40 standard engaged with said disk, means for rotating said standard whereby to impart rotary movement to the said disk and plate, means releasably engageable with 45 said plate for preventing the rotation thereof when desired, and means carried by the said standard for locking the same against rotation.

9. In a switch stand of the class described, a base, a plate rotatably connected with 50 said base, a pitman rod carried by said plate and adapted to be connected to the switch points of a railway switch, means upon the base, movable into and out of engagement with the plate for preventing the 55 rotation of the said plate, a substantially vertically disposed standard supported by said plate, and separate means for locking the said standard against rotation.

10. In a switch stand of the class described, a base, a plate rotatably mounted upon said base, a disk removably supported upon said plate and rotatable therewith, a supporting platform also carried by said base, a substantially vertically disposed 65 standard journaled in said platform and

engageable with said disk, a pitman rod connected to and movable with said plate, and being adapted to be suitably connected with the switch points of a railway switch, means for rotating said standard whereby rotary movement will be imparted to the said disk and plate, and means for locking said standard against rotary movement. 70

11. In a switch stand of the class described, a base, a plate rotatably mounted 75 upon said base and provided with notches, a disk removably supported upon said plate and rotatable therewith, a supporting platform also carried by said base and provided with notches, a substantially vertically disposed standard journaled in said platform and engageable with said disk, a pitman rod connected to and movable with said plate and adapted to be suitably connected with the switch points of a railway switch, 80 a latch carried by the base and adapted for selective engagement with the notches in said rotatable plate for preventing the rotation thereof, an arm carried by said standard above said platform, and a lever 85 pivotally carried by said arm and adapted for selective engagement with the notches in said supporting standard, whereby to lock the said standard against rotation when 90 desired. 95

12. In a switch stand of the class described, a base, a plate rotatably mounted upon said base and provided with notches, a pitman rod connected with said plate and adapted to be connected with the switch 100 points of a railway switch, a standard supported by and rotatable with the said plate, a shaft mounted upon the base, a latch fixed upon the shaft and engageable in said notches selectively when the plate is rotated 105 to aline one or the other of the said notches with the latch, a lever fixed upon the said shaft, a weight upon one end of the lever constituting means for overbalancing the 110 shaft to effect engagement of the latch in said notches, and a foot pedal carried by the lever at its other end.

13. In a switch stand of the class described, a base, a plate rotatably mounted upon the base and provided with notches, a pitman rod connected with said plate and adapted to be connected with the switch points of a railway switch, the plate having upstanding radially disposed lugs upon its 115 upper face, a disk disposed upon the plate and having radial recesses accommodating the said lugs upon the plate whereby the disk is connected with the plate for rotation therewith, a standard rotatable with the disk, and means carried by the base and engageable selectively in the notches of the 120 plate for locking the plate against rotation. 125

In testimony whereof I affix my signature.

PETER FRANDSEN.
